DESIGN FOR A GATE

Cristobal Baca, Albuquerque, N. Mex., assignor of fifty per cent to Aurora C. Padilla, Albuquerque, N. Mex.

Application February 20, 1947, Serial No. 137,049

Term of patent 14 years

(Cl. D28—1)

To all whom it may concern:

Be it known that I, Cristobal Baca, a citizen of the United States, residing at Albuquerque, in the county of Bernalillo and State of New Mexico, have invented a new, original, and ornamental Design for a Gate, of which the following is a specification, reference being had to the accompanying drawing, forming part thereof.

The figure is a perspective view of a gate, showing my new design.

I claim:

The ornamental design for a gate, as shown.
CRISTOBAL BACA.
